(57) CLAIM

The ornamental design for a transaction card, as shown and described.

DESCRIPTION

FIG. 1 is a front, perspective view of a transaction card showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The features shown in broken lines are portions of the transaction card forming no part of the claimed design. The features shown in long dash-short dash broken lines indicate the bounds of the claimed design and otherwise form no part of the claimed design.

1 Claim, 5 Drawing Sheets
